UNITED STATES PATENT OFFICE

JOSEF MAYER, OF KARLSBAD, CZECHOSLOVAKIA, ASSIGNOR TO THE PHILAD COMPANY,
OF CLEVELAND, OHIO, A CORPORATION OF OHIO

HAIR WAVING APPARATUS

Original application filed July 18, 1929, Serial No. 379,235. Divided and this application filed July 28, 1930. Serial No. 471,133.

This invention relates to apparatus for use in the waving of hair upon the human head and more particularly to means for holding the hair in proper position while the same is treated to produce the desired wave.

5 An object of the invention is to provide an improved means for winding the hair and returning it during the waving process.

Another object is to provide an improved 10 means for supplying moisture to the hair.

Another object is to provide improved moisture supplying elements, and means for attaching the same to other parts of the apparatus.

15 Other objects will hereinafter appear.

The invention will be better understood from the description of one practical embodiment thereof, illustrated in the accompanying drawings, in which:

20 Figure 1 is a perspective view of a protector or clamp used to hold a strand of hair while being treated, together with a curler rod, and moisture retaining pads;

Figure 2 is a perspective view of the 25 protector or clamp alone in open position;

Figure 3 is a plan view of the protector of the above figures in closed position;

Figure 4 is an end elevation thereof;

Figure 5 is a section on the line V—V of 30 Figure 3;

Figure 6 is a side elevation of the clamp and rod showing the manner in which these are applied to a strand of hair; and

Figure 7 is a section of the parts shown 35 in Figure 6, taken on the line VII—VII thereof, showing in addition the position of the moisture retaining pads and electric heater used therewith.

The apparatus illustrated is for use in those 40 waving processes in which the hair on the head of the subject is divided into flat strands which are wound spirally, one turn immediately over another, upon a curling rod, placed under tension, and subjected to heat 45 and moisture to produce a lasting or "permanent" wave.

The clamp or protector comprises two arms 1 and 2, each having a metallic frame member or reinforcement 3 or 4 consisting of two 50 superposed flat bars extending throughout

its length, and a covering 5 of heat insulating material, shown as compressed ground cork. The reinforcement bars are each made of either two pieces riveted together, or of one piece and folded upon itself, and their edges form channel-like recesses 6 in which are received rubber strips 7 which bear upon the strand of hair, resiliently retaining it firmly between the arms of the clamp.

55 The metallic bars are pivoted at one end of the clamp by a link 8 and a rivet 9, and to one of the bars 3, at its other end, is pivoted by means of a rivet 10, a latch 11 having a rolled or enlarged end 12, the latch being arranged to be swung between the halves of the 60 ends of the other bar 4 with the enlargement bearing on their outer edges to retain the 65 parts of the clamp in closed position, as shown in Figure 3.

70 The ends of the bars adjacent the pivoted link 8 are bent upwardly to form bearing members 13 in which the ends 14 of wire loops 15 are pivotally inserted, the free ends of the loops being arranged to snap over the headed ends 16 of rivets 17 adjacent the free 75 ends of the reinforcement bars. These retaining members are used to retain a fabric of absorbent covering for the hair strand being treated during the waving process. A pin 18 extends upwardly from latch 11 to 80 receive the retaining mechanism of the curling rod.

85 This rod consists of a spool-like shell 19 gradually narrowing from its ends to its center and provided with perforations 20. A retaining tongue 21 is pivoted to the shell adjacent one end by a rivet 22 and is adapted to retain the ends of a strand of hair while being wound about the rod.

90 Within the shell, adjacent the other end, is a plug 23, having a serrated outer surface 24 arranged to constitute one element of a ratchet mechanism, the plug being rigidly secured to the shell. A second plug 25 having a complementary serrated end is loosely inserted within this end of the rod and retained therein by a washer 27 at the extreme end of the rod, over which the end of the shell is rolled. A central lug 28 integral with the 95 second mentioned plug extends through the 100

washer and is perforated at 29, to be slipped over the pin 18 carried by the latch. A compression spring 30 surrounds this lug and is positioned between plug 25 and the washer 5 to resiliently press the serrated faces and the two plugs into engagement.

The operation of the apparatus is as follows: The hair is divided into flat strands and one of these is clamped adjacent the wearer's 10 scalp between the two arms of the clamp. The ends of this strand are then placed upon the curling rod and the tongue is closed upon them to retain them thereon. The rod is then rotated by the operator until substantially 15 all the hair has been wound upon it, one turn above another, this winding, of course, bringing the rod closely adjacent the clamp. The hole in lug 28 is then slipped over the pin 18 upon the clamp, and the rod 20 can be further rotated by the hand of the operator to tighten and stress the wound hair, the ratchet elements allowing it to be rotated in one direction but preventing its rotation in the other.

25 After the hair has been completely wound, a pad or flannel containing a desired waving solution is wrapped about the wound strand. This covering is shown as made in two parts 31 and 32, although only one may be used if 30 desired. Each part consists of a rectangular piece of flannel fabric or the like, provided with a seam 33 along one edge which is adapted to be slipped over one of the loops 15, so securing this edge along one arm of 35 the clamp. When two-part covering is used, the parts are overlapped, as shown in Figure 7, while if a single piece is used, this is made large enough to overlie the entire wound strand. After this it is only necessary to 40 apply a heater 34 over the coiled strand and supply heat to the same for the time necessary to cause the desired wave to be effected. One heater which is particularly well adapted for use with the above apparatus is such 45 as is shown in my prior Patent Number Re. 17,585. The heater and clamp together form a substantially continuous cylindrical chamber enclosing the rod, wound strand of hair, and pad or flannel.

50 While I have described the illustrated embodiment of my invention in some particularity, this is done by way of illustration only, it being obvious that many other embodiments will readily occur to those skilled in this art, and I do not, therefore, limit myself to the precise details shown and described but claim as my invention all embodiments coming within the scope of the subjoined claims.

55 I claim:

1. A clamp for use in hair waving comprising two metallic bars pivoted together at one end, a latch connecting their other ends, a covering of heat insulating material on said bars, means for securing a pad upon the

upper surface of one of said bars, said means consisting of an arm pivotally connected at one end to said bar, and means for detachably connecting the other end of said arm to said bar.

2. A clamp for use in hair waving comprising two metallic bars pivoted together at one end, a latch releasably connecting the other ends thereof, a covering of heat insulating material on said bars, means for securing a pad upon the upper surface of one of said bars, said means comprising a wire loop pivoted at one end to one end of said bar and a stud projecting from the other end of said bar, the loop being formed with an end arranged to snap over said stud.

3. A clamp for use in hair waving comprising two bars pivoted together at one end, a latch releasably connecting the other ends thereof, a covering of heat insulating material on said bars, means for securing a pad upon the upper surface of one of said bars, said means consisting of a wire loop pivoted at one end to one end of one bar, a stud projecting from the other end of said bar, the loop being formed with an end arranged to snap over said stud.

In testimony whereof I hereunto affix my signature this 8th day of July A. D., 1930.

JOSEF MAYER.
